(CL. 91—3)

To all whom it may concern:

Be it known that we, Roy H. Zinkil and Henry Dreyfuss, citizens of the United States, residing at Oak Park and New York, in the counties of Cook and New York, and States of Illinois and New York, respectively, have invented a new, original, and ornamental Design for a Cover Plate for a Beveled Panel Back Lavatory Supply and Waste Fitting or the like, of which the following is a specification, reference being had to the accompanying drawings, forming part thereof.

Fig. 1 is a plan view of the cover plate embodying our design.

Fig. 2 is a front view thereof.

Fig. 3 is a side view thereof.

Fig. 4 is a rear view thereof.

Fig. 5 is a plan view positioned in a 45-degree angle mounting.

We claim:

The ornamental design for a cover plate for a beveled panel back lavatory supply and waste fitting or the like, substantially as shown.

ROY H. ZINKIL.
HENRY DREYFUSS.
